UNITED STATES PATENT OFFICE

2,625,628

HIGH-VOLTAGE CIRCUIT BREAKER

Joseph D. Wood, Upper Darby, Pa., assignor to
I T E Circuit Breaker Company, Philadelphia,
Pa., a corporation of Pennsylvania

Original application January 11, 1947, Serial No.
721,648. Divided and this application June 28,
1947, Serial No. 757,739

2 Claims. (Cl. 200—147)

1

My present invention, which is a division of U. S. application Serial No. 721,648, filed January 11, 1947, relates to high voltage high capacity circuit breakers, and more particularly to circuit breakers having an interrupting rating of 50,000 kva. and better in any voltage range between 2300 and 5000 volts and at current ratings of 600 and 1200 amperes.

In high capacity circuit breakers which are designed to interrupt arcs of substantial kva., it frequently occurs that the blow-out mechanism will effectively move the arc into the arc chute causing it to be extinguished at or near the full rated interrupting capacity, while the blow-out mechanism is not able to perform the job of moving the arc up into the arc chute at very low current values represented by the charging currents of transformers or cables owing to the fact that the flux through the blow-out mechanism or coils is very low and ineffective. This has resulted, in some prior art circuit breaker construction, in the addition of further devices such as puffers and the like to assist the blow-out coil in performing its operation. Alternatively the prior art blow-out coil has been provided with sufficient turns to obtain the required ampere turns even for low current failures. Such prior art devices have thus utilized the expedient simply of assisting an ineffective construction by adding additional construction thereto rendering is unnecessarily bulky.

A primary object of my invention is the arrangement and construction of the blow-out mechanism of my novel circuit breaker so that it may move an arc at low interrupting current as well as an arc at high interrupting current properly into the arc chute so that the same may be extinguished; the said blow-out mechanism operating for this purpose over the entire range of interrupting capacity of the circuit breaker without the necessity for additional aid or other expedients. This I achieve in part by passing only a portion of the arcing current through the blow out coils, the percentage of such current decreasing as the fault current increases. For very low value currents, I provide a separate arc chute.

In the construction of high voltage circuit breakers, an important problem always present is the transfer of the arc from the main contacts to the arcing contacts. An object of the present invention resides in a novel construction of main and arcing contacts and of an auxiliary contact with relation to the movable contact

2

arm for a rapid transfer of the arc to the auxiliary contact and movable contact.

In accordance with the present invention a novel circuit arrangement is provided for the blow-out coil whereby the arc formed on opening of the contacts is in parallel with the blow-out coil and provides a by-pass circuit around the blow-out coil of a predetermined impedance in relation to the impedance of the blow-out coil.

Accordingly a further object of the present invention is the provision of novel by-pass arcing circuits in relation to the blow-out coil.

The foregoing and many other objects of my invention will become apparent from the following description of the drawings in which

Figure 1 is a side view in perspective, partly broken away showing my novel circuit breaker assembled and mounted on a truck.

Figure 2 is an enlarged side front view in perspective partially broken away showing the lower terminal assembly, upper terminal assembly, the blow-out coil assembly and the movable contact bridge assembly.

Figure 3 is a detail of the construction of the front end of the lower terminal of my novel circuit breaker.

Figures 4 and 5 are schematic views of the arcing contacts and blow-out coil of my novel circuit breaker.

Referring now to Figures 1 and 2, my novel circuit breaker is shown preferably mounted on a movable truck. The movable truck comprises a back main supporting structure which includes the vertical support members 10 and 11 connected together and interbraced at the lower end by the Masonite panel 12 and at the central and upper portion by the cross-bars 13, 14 and 15 which are connected as shown, in any appropriate manner, as for instance by bolts and nuts to the vertical members 10 and 11. The lower ends of the vertical members 10 and 11 are provided with bearings 17 and 18 for the shaft 19 which carries the rear wheels 20 and 21 of the truck. The vertical members 10 and 11 together with the cross bracing elements above described and the wheels 20 and 21 constitute a single unitary member of assembly.

Certain of the assemblies are standard and require no specific discussion here. Thus, the control panel assembly 47 and the trip unit assembly 48 may be substantially standard units which require no specific description. Also, the control switch contacts indicated generally at 70 of Figure 1 and the grounding contacts 11, 72 of Figure 1 may be standard units. The essential elements

as above pointed out with respect to these units is the unit assembly arrangement which is possible with the construction herein shown.

The rear end of the operating mechanism assembly 46 is supported on the cross bar 74 which is held by the bolts 75, 75 across the top of the lower panel 12. Cross bar 74 also provides means for supporting additional assemblies. The specific novel assemblies or sub-assemblies shown in Figure 1 and forming an essential part of the novel circuit breaker here shown are the lower terminal assembly shown in Figure 2, the upper terminal assembly of Figure 2, and the movable contact arm or bridge assembly of Figure 2. The specific operation of these individual assemblies renders possible the entire high speed high capacity circuit breaker which my novel unit embodies.

The various assemblies above mentioned will be described in order, going from the bottom toward the top of the circuit breaker without specific emphasis on any one of the assemblies over the other.

It must be emphasized, however, that an important feature of the circuit breaker is in the novel arc chute construction in conjunction with the novel blow out construction.

The operating mechanism utilizes as closely as possible the simple principle of the lever operated switch with only enough addition thereto to provide automatic response to over-current conditions in order to trip the circuit breaker and also to provide a solenoid closing means. The simplification of this operating mechanism makes possible the production of the inexpensive circuit breaker herein described.

Thus, while the arc chute assembly and the blow-out assembly make possible the high capacity operation and high speed operation which are essential to the operation of the circuit breaker as a whole, the simplicity of the other assemblies makes possible the economical and efficient construction.

The individual unit assemblies facilitate storage of parts preparatory to final assembly and thus makes it possible to fill orders quickly.

Thus the first sub-assembly which consists of the back panel and the back wheels 20 and 21 is essentially a simple flat member which may readily be stored and does not take up any substantial amount of space (see Figure 1).

Heretofore, the difficulty encountered in pre-manufacture of sub-assemblies in anticipation of future orders resided in the fact that the main frame of the circuit breaker or other switch gear usually was as big as the circuit breaker itself, so that the manufacture and especially the storage of the main frame presented the same problem as the storing of an entire circuit breaker. No real economy was effected by pre-manufacture of the main frame since the entire circuit breaker could be stored just as readily.

By means of my novel device, the back panel and the rear wheels of the truck which constitute a single flat structure may readily be stored awaiting specific orders for assembly or specific circuit breakers.

The truck structure is completed by means of a lower or bottom platform 23, which carries a front wheel 24 in the front swivel 25 (Figure 1). The bottom platform 23 is secured at the rear end to the lower end of the vertical members 10 and 11 above the bearings 17 and 18 for the rear wheel. The bottom platform 23 in connection with the back panel form the vertical support-

ing members 10 and 11 and their interbracing structure and taken together with the rear wheels 20 and 21 and the front swivel wheel 24 comprises the truck or mounting for the circuit breaker. Thus the bottom platform 23 and the front swivel wheel 24 constitute a single sub-assembly which may readily be stored without requiring any additional space and which may readily be attached by two screws to the lower end of the vertical members 10 and 11.

This type of unitary sub-assembly construction which may readily be interconnected with other elements in order to make a complete truck, facilitates modification and of variation of sub-assemblies in order to meet the specific orders.

Thus in the event various control elements must be multiplied to a substantial extent in the final circuit breaker thus requiring perhaps a custom built lower platform 23, this lower platform 23 may be built to the unique specifications of the customer and may then be combined with the standard back panel construction which is kept in stock. However, the entire truck construction including the first and second sub-assemblies above described are built in full anticipation of all requirements to which the particular circuit breaker may be put, so that particular custom made back or bottom portions of a truck will be required only in exceptional cases. The upper terminal assembly 30, and the lower terminal assembly 31 for each of the three poles is formed from a single bar of copper of rectangular cross section appropriately insulated by phenolic insulation as described more specifically hereinafter in connection with Figure 2. The terminal assembly elements 30, 31 are carried by the vertical supports 10 and 11, as well as the central vertical support 32 which is carried between the lower Masonite plate 12, and the upper cross bar 14, as shown in Figure 2.

Each of the vertical members 10, 11 and 32 is recessed at 33, 33 to receive the terminal members and accurately position the same.

Each of the upper and lower terminal assembly members 30 and 31 also carry the spring biased disconnect contact elements 38, 38 also hereinafter more specifically described in connection with Figure 1, but shown also in Patent Number 2,029,028. The intermediate cross bar 13, which is secured to the vertical members 10, 11 and 32 by the bolts 40, also carries at its outer end the wheels 42 on an appropriate shaft extension thereof, the said wheels 42 cooperating with appropriate tracks in the compartment to guide the truck into and out of the compartment properly.

The racking and indicator assembly shown generally at 43 of Figure 1 also carries the front wheels 44, 44 to ride on the guide tracks of the compartment in which the circuit breaker is housed.

The racking and indicator assembly 43 is supported from the mechanism assembly. The control panel assembly 47 is supported by the lower platform 23 of the circuit breaker as is also the trip unit assembly 48. The solenoid closing mechanism 49 is a part of the operating mechanism assembly 46.

The movable contact assembly shown generally at 50 of Figures 1 and 2 is connected at its lower end to the lower terminal assembly 31 in the manner hereinafter described, and is provided with a link 51 which is connected to the contact operating arms 52 projecting up from the operating mechanism assembly 46. The movable contact bridge assembly which of course has as many

poles as there are upper and lower terminal assemblies, three in the particular instance shown, is provided with contact elements hereinafter more particularly described in connection with Figure 2. The blow out coil assembly 53 which includes the coil 54 of Figure 2 and the laminated blow out iron legs 55, is mounted on the upper insulating back panel 56 also across the bars 15 and 14 and the upper portion of vertical supporting members 10 and 11 and is supported thereby.

It is spaced from the bars 10, 11, 32, 14, 15 by the upper insulating back panel 56 which panel is secured across the bars 10, 11 and 32 as shown in Figure 2. Appropriate openings 59, 59 are provided in the panel 56 to permit the terminal members 30 and 31 to project therethrough in a manner shown in Figures 1 and 2.

The arc chute assembly 57 is supported by the blow out assembly 53 and particularly by the laminated legs 55 of the blow out iron which ride between the bracing bars 58, 58 on each side of the arc chute as shown in Figure 1 and as will be more specifically described hereinafter in connection with Figures 1 and 2.

Lower terminal assembly

The lower terminal assembly 31 shown in Figures 1 and 2, comprises a bar of copper 150 insulated by an oblong Bakelite tube 151 with a conductive inner lining into which it has been pressed. The front end 152 supports the movable contact bridge assembly 50 in a manner hereinafter specifically described, while the main disconnect contacts 38 are secured to the rear end 154.

The lower terminal 31 has the side flanges 155, 156 secured thereto in any suitable manner, to cooperate with the movable contact arm as shown in Figure 2. In the usual procedure for insulating a terminal bar such as that shown in Figures 1 and 2 phenolic insulation material is wrapped around the bar and tightly pressed thereon. This is a complicated process which must be performed on special machinery and by those having special skills in the field.

In the present construction, instead of wrapping phenolic insulation tightly around the bar 150, the flat tube 151 is used, said tube being provided with a conductive lining 162. This tube is placed over the bar 150 and then pressed into tight engagement with the bar 150 to provide the insulation cover therefor.

The principal reason for wrapping the insulation in the prior art was that no minute air pockets could be permitted since at high voltages these would result in corona discharge, causing progressive dielectric deterioration and thereby resulting in breakdown of the insulation. Consequently great care was required in the wrapping of the insulation.

I have discovered that by using a sleeve of insulating material and making the inner surface of the sleeve conductive, the sleeve may simply be pressed down around the tube to conform with the contour of the bar and provide a completely engaging surface to surface contact thus accordin any deleterious effects resulting from any minute air pockets that may remain. Thus where the prior cost of wrapping such bars was in the neighborhood of \$12.00 per bar and it was necessary to send the bar out to be wrapped by special machinery, my invention makes possible the insulation of the bar at the circuit breaker plant at a cost of about \$1.50.

Upper terminal assembly

The upper terminal assembly 30 shown in Figures 1 and 2 also comprises a bar 160 of copper having an insulating sleeve 161 mounted thereover in the same manner as previously described in connection with the lower terminal assembly Figure 2.

The rear end of the bar 160 has the conformation 164 to receive and hold the main disconnect contacts 38 shown in Figure 1. The front end of bar 160 has secured thereto the stationary main contact 167 and the stationary arcing contact 166 (Figure 2). The upper end of the front portion of bar 160 has secured thereto the insulating blocks 165 and 168 (Figures 1 and 2), which have secured thereto the insulating plate 170 having the upper slotted extension 170a. Connector 171 is secured in any suitable manner to the insulating blocks 165 and 168 but is insulated from the contact bar 160 and the arcing contact 166 and stationary contact 167.

Connector 171 has a cut away portion at its front end between which, and spaced from either edge, the forward end 203 of the movable contact arm 204 comes to rest when the contacts are in engagement as will be described hereafter.

Movable contact assembly

In Figure 2, I have shown one of the contact arms 80. The contact arm 80 comprises a pair of copper bars 180, 181 between which is secured, at the upper end by pin 205, the arcing contact arm 204. The movable arcing contact-arm 204 is held in proper spaced relation by the spacer washers 184—184, all of which are forced into proper current carrying relation by the spring washers 233—233. The upper inside edge of the copper bars 180—181 carry special arc resisting silver alloy contact blocks 185 which comprise the main movable contacts.

The lower ends of the bars 180 and 181 are provided with the registering openings to receive the pin 187 (Figures 1 and 2) which pin passes through the openings and through the slotted openings 188 (Figure 3) of the front end 152 of the lower terminal 31 which is received between the arms 180—181.

The pin 187 is provided on each side with a lug 190 (Figures 1, 2 and 3) carrying the bar 191 which passes through openings 193a (Figures 2 and 3) of the side flanges 156. Compression springs 193 on each side are captured between flanges 156 on each side and the lug 190 of pin 187 on each side thus forcing the lower end or pivot of the contact arm out toward the right with respect to Figures 1 and 3 at the pivot point 186.

The contact arm effectively pivots about pin 200 (Figures 1 and 2) which is connected between the arms 181 and 180 and which carries the end of link 51 connected to contact operating arm 52. Thus, compression springs 193 force the contact arm 80 to rotate counterclockwise about the pin 200 within the limit of the length of slot 188 on the lower terminal and thus forces the movable contact 185 into close wiping engagement with the stationary contact member 167 (Figures 1 and 2).

In any position of the arm 80 other than the closed position of the arm 80, compression springs 193 push the pin 187 over to the far right end slot 188 of the lower terminal of Figure 2. When the contact arm reaches the closed position of the contacts, the movable contact 185 bears against the stationary contact 167 and as the link

51 forces pin 200 and contact arm 80 into the closed position, the spring 193 yields because of the slope of the angular slot 188 to permit the wiping action to occur between the contacts 185 and 187 and the contacts to close firmly.

The forward end 152 of the lower terminal of Figure 2 is provided with silver alloy inserts 202, 202 to bear against the inner surfaces of arms 180, 181 of contact arm 80. Thus it will be seen that no pigtails are used, but appropriate elements are used on pin 187 to squeeze the lower ends of arms 181, 180 against the insert contacts 202 on the lower terminal.

The contact springs 193 are located close to the pivoted stud 187 which is a distinct advantage because they are well away from the arcing zone. The connection of link 51 to the contact arms is at a point 200, as above pointed out, well above the center point of the arms 80, so as to make these contacts blow-on contacts as explained in the following description.

In response to a rise in currents, magnetic forces developed in these contacts tends to increase contact pressure at all contact points. The arcing contact arm 204 is pivotally mounted on the pin 205 between the contact arms 180, 181 and the spacer washers 184, and is provided with an arcing contact element 206 and the horn 207. The lower end of arcing contact arm 204 is connected by the floating pin 210 to the link 211 which in turn at this lower end bears against the milled surface 212 of the milled pin 213 carried between the springs 180, 181.

Tension spring 215 connected between lug 216 and spring eye 217 is arranged to rotate link 211 clockwise around the bearing furnished by the milled portion 212 of pin 213. The lug 216 is adjustably mounted on screw 220 which in turn is received in the tapped opening 221 of pin 222 carried between the arms 180, 181. Rotation of screw 220 results in moving lug 216 to change the tension of spring 215 and thus increase the bias thereof.

Spring 215 thus acts on links 211 to cause the toggle 211-210-204 to collapse in a direction to force the arcing contact 206 to the left. The full collapse of this toggle is prevented by the adjustment of screw 220 which bears against the end 225 of arcing contact arm 204. Tension spring 215, however, thus drives the arcing contact element 206 out to the left with respect to Figure 2 where it will make contact with the stationary arcing contact 166 before the main contacts engage and where it will maintain contact with the stationary arcing contact until after the main contacts have separated.

Since the center 205 of arcing contact arm 204 is well above the mid-point thereof, a blow-on action of the arcing contact occurs, also thus ensuring that the arcing contacts will remain firmly in engagement until the main contacts have separated.

The position of the arcing tips 206 above the main contacts 187 forms an upward loop in the circuit which tends to initiate a blow out action to start the arm upward when drawn.

In order to protect the lower terminal structure against any possible defect in the arc chute or blow-out mechanism which would tend to drive an arc down, an insulating shield 230 is provided secured to the screws 183 and flared out to protect the uninsulated portion of the lower terminal bar 150.

Spring 215 ensures that the movable arcing contact will move into engagement with the station-

ary arcing contact as the contact arm begins to open and before the main contact separates. The arcing contacts will then stay in engagement for a substantial portion of the opening movement depending on the setting of screw 220 (Figure 2).

Blow out assembly

The blow-out assembly 53 comprising the coil 54 and the laminated blow-out iron legs 55 already referred to in Figure 1, is shown more specifically in Figure 2. The coil 54 is connected by the lead 235 and bolt 236 (Figures 1 and 2) to the upper terminal bar 160. The opposite end of coil 54 is connected by lead 238 to extension 171a on contact bar 171 passing through a slot in the upper extension 176a of insulating strip 170 (Figure 2). Coil 54 is wound on an iron core 240 to which is secured the laminated blow-out iron legs 55 on either side.

I have found that preferably four such side plates on each side $\frac{1}{8}$ " thick ensures a proper distribution of magnetic blow-out flux over the full length of the side plates. Also I have found that in order to obtain a proper blow-out flux without inserting too much impedance in series with the arc it is desirable that the coil 54 consist of 18 turns of copper strips of $\frac{1}{16} \times \frac{3}{8}$.

The side frame members 242, 242 (Figure 2) of the blow-out assembly are secured against the core 240 by bolts 243 which also secure the plates 55 against the core. The side frame members 242 of the blow-out assembly have secured therebetween the upper block 245 by means of pin 246 and the lower block (not shown) by means of pin 248 and plate 249 by means of screws 250.

Block 245 and its corresponding lower block are provided with tapped openings by means of which the entire blow-out assembly may be readily secured to the frame of the circuit breaker. It will thus be seen that the entire blow-out assembly may be readily mounted on and removed from the circuit breaker as a single unit.

Arc chute

The blow-out assembly serves as support for the arc chute described in Figure 2. The arc chute assembly 57 mounted above the contact assembly 80 provides for a positive and efficient arc interruption. It consists of insulation side walls 257, front and back arc runners 294 and 299 respectively (Figure 4) and a series of ceramic plates 259 mounted in spaced relation transverse of the arc path and a strong magnetic blow-out field to force the arc into the arc chute.

The sides 257 have fastened at their lower portion, adjacent the arcing area, inner arc resisting insulating plates 258-259 of special composition hereinafter described. The arc resisting plates 259 are chamfered along their upper edges at 252-252 to provide a straight locking edge for the cross plates 260 and the spacers 261. The lower ends of the cross plates 260 and the spacers 261 are appropriately shaped to fit the chamfered edge 252.

As the arc is driven into the chute by the magnetic field, it passes rapidly through the arc extinguishing ceramic plates 259 which are rectangular in shape at the top and have a long tapered lower edge extending from the center of one side of the plate to the lower corner on the opposite side of the plate. A ceramic spacer 261 is provided to support each plate and position it with respect to adjacent plates and forms with the long tapered surface of the plate, a triangular opening with the apex at the top of the pas-

sage of the arc. Each plate with its spacer presents a decreasing area for the arc as it rises and gradually squeezes it into a narrow slot 307.

The plates 260 are assembled alternately in an interleaved relation and spaced from each other so that the long tapered surfaces cross at the center of the chute directly above the path of the arc as it travels up the chute. As the arc passes the crossover point of the plates it is forced into a zig zag or sinuous path gradually but rapidly increasing its length and bringing it into contact with larger and larger cool surfaces of the plates. The arc must thus bend around the edges of the plates which are effective in circuit interruption. The positive and efficient arc interruption is affected by the cooling, lengthening and squeezing of the arc at numerous points all along its path.

Provision for the interruption of low current arcs is built into the arc chute. No moving parts or auxiliary equipment are necessary. Short circuit or normal overcurrents are extinguished before the moving arc horn 207 passes the front arc runner 291. The arc formed by currents of low value is extended in the chute beyond the front arc runner 291 and effectively cooled and deionized by a set of plates 322 located in the current path.

The side plates 257 are connected together at the front and back end of the arc chute by bolts 268. The side plates are provided with insulating bracing bars 58 secured thereto by the bolts 268 and spaced apart by the width of the laminated blow-out iron legs 55.

The materials used in the construction of the arc chute play an extremely important part in the performance of the circuit breaker.

The side plates 257 are made of Bakelite with a layer of fibre on each side. During interruption not only full voltage is applied to these plates but frequently switching surges of very high value are encountered. The high insulating value of Bakelite is desired but it alone would not be satisfactory since it has the characteristic of carbonizing and "tracking" if any arc or high temperature arc gases come in contact with it. Consequently, the Bakelite is coated with fibre which does not have this characteristic. Furthermore, an arc-resisting insulating varnish is applied to the fibre to keep it from absorbing moisture. Furthermore, the spacers 261 for the cross-plates 260 completely line the inside of the arc chute in the lower part where the arc is drawn and prevents the arc coming in contact with the side plates at any point.

The material of which the cross plates 260 and the spacers 261 are made, determines to a large extent the ability of the breaker to interrupt currents. The least expensive material that is at all suitable for this application is the asbestos cement board called Transite. This material gives fair operation and for low interrupting capacities is quite suitable. In an effort to increase the interrupting capacity, numerous materials were tried. Gas forming materials such as fibre were found to be unsatisfactory as they increased the display incident to circuit interruptions and the excess gas had a tendency to initiate arcing in other parts of the breaker. Inert materials were better. Porcelain, while quite good was too fragile and could not be manufactured in thin plates with sufficient accuracy to make it practical.

By far the best material found was the glass bonded mica consisting of mica dust and glass fused and pressed at high temperature and pres-

sure. It is inert at the temperatures encountered in the arc chute, an excellent insulator, does not absorb moisture and is a nongasforming material. This material when used for the arc plate and spacers increased the interrupting capacity to more than twice the value shown by other materials. It is used not only for the cross plates 260 and spacers 261 but also for the arc resisting plates 269 that come in contact with the arc.

The arc chute may be mounted in position by being slid on to the laminated blow-out iron legs 55 so that the reinforcing bars 58, 58 act as runners to receive the laminated legs 55 in the manner shown especially in Figure 1, thus holding the arc chute in position.

In order to ensure a further distribution of magnetic blow-out flux down into the region of the contacts, an additional iron plate 270 (Figure 1) is provided on each side of the arc chute secured to the bracing bars 58 by screws 271 and having extension 272 extending down into the region of the contacts outside the plates 57.

The blow-out flux through the laminated blow-out iron legs 55 is also communicated to plate 270 and by extension 272 is communicated down into the region of the contacts to increase the blow-out effect in that region. The runners or bracing bars 58 on one side of the arc chute are provided with the bronze springs 280 connected between the runners or bracing bars 58 by screws 281 and a latch assembly 61 secured thereto in any suitable manner as by screws 283, 283 and having a projection 282 which engages a corresponding detent 284 in the laminated iron leg 55 (Figure 1). Thus the arc chute is supported by the laminated legs 55 between runners 58 on each side and is latched in position by the latch assembly 61 engaging detent 284 in laminated legs 55. To remove the arc chute it is only necessary to press in the latch assembly 61 to disengage the detent 284 from laminated iron legs 55 so that the arc chute may be slid out. As already stated, the arc chute is provided with a back arc runner 299 and a front arc runner 291 converging below the arc chute and toward the center in the region of the contacts, the front arc runner 291 having extension 291 toward the contacts and the further rearward extension 293.

The portion 171A (Figure 2) of the upper terminal to which lead 238 of the blow-out coil is connected is also provided with the spring clip 300 (Figures 1 and 2) to receive the rearward extension 293 of the rear arc horn 290 of the arc chute 57. Thus no special connection need be made for the arc chute; but when the arc chute is slid into position, the rear extension 293 of the rear arc horn 290 moves into the spring clip 300 and the rear arc horn is thus connected to the end 238 of blow-out coil 54.

The section 290B of the rear arc horn rests on plate 171 to obtain further contact to the rear arc horn 290. Thus when the section of the arc on the stationary arcing contact jumps to section 290A of the rear arc horn, the current path is from terminal 30, bolt 236 to lead 235 to coil 54 to lead 238 to section 171A of member 171 and spring clip 300. Then from spring clip 300 to section 290B of rear arc horn 290. Then through the arc chute to the movable arcing contact and then to the front arc runner 291 as hereinafter more specifically described.

The cross plates 260 are each of an insulating non-carbonizing material, preferably a glass bonded, mica ceramic material or of a material known as Transite. These plates are longitudi-

nal members having a curve at section 303 of a very large radius; upward of this position they have a curve 304 of smaller radius; and above that position have an extension 305 entering the notch 268 and closing off that side of the plate.

The side of each plate opposite the curve is flat. When the arc is first drawn it is driven up by the blow-out mechanism into the notch 310 of V-shaped cross-section formed by the curves 303-304 of the alternately arranged plates. As the arc is driven up further beyond the apex of the notch, it is caused to zig-zag laterally in flowing past the curves 304 of the alternately arranged plates. It thus passes through the relatively narrow notch 307 on one side of one plate and then through a similar relatively very narrow notch on the opposite side of the alternate plate and back and forth laterally through the arc chute.

If the arc is not extinguished when the arc has reached this point, the magnetic blow-out blows the arc up still further past extension 305 where in addition to the lateral zig-zagging and lengthening of the arc, the arc is zig-zagged vertically. This combination of extreme lateral zig-zagging with vertical zig-zagging of the arc ensures extinguishment of the arc before the top of the arc chute is reached. The combination of lateral zig-zagging with vertical zig-zagging limits the upward travel of the arc.

Thus it will be seen that one of the essential elements of the arc chute herein described is first the lateral zig-zagging or lengthening of the arc as it is blown up into alternating thin narrow slots on each side. Thereafter the portion of the arc between the cross-plates 280 is free to move up to superimpose on the lateral zig-zagging or lengthening of the arc, a vertical zig-zagging or lengthening.

Also it will be seen that there is no connection whatever between the front arc horn 291 and the lower terminal or any other terminal when the circuit breaker is closed or open.

The effect on the arc between 171-B and 288 which is horizontal is to drive it rapidly up the runners 290 and into the arc chute 57. The effect on the arc between 171-B and 166, which is vertical, is to drive it back against the insulating and heat resisting block 168. This insulating block may be provided with slots, grooves, holes 163 (Figure 5) or other cooling means to deionize the arc and effect the blow-out characteristics of the breaker. It will be apparent that the size, shape and spacing of the extensions 272 will also effect the blow-out characteristics.

It will also be noted that the conductive bar 171 has a U notch indicated generally at 171B therein, in which the portion 298 of the upper arcing horn 207 registers, thus provided for simplified transference of the arc to the contact bar 171 and hence to section 298a of the rear arc runner 290 of the arc chute 57.

The insulating shield 239 above described in connection with Figure 3 prevents a low current arc from being blown down accidentally contacting the terminal 31. Oscillograph tests have shown the rates of arc extinguishment ranging from .58 cycle at 63,200 kva. (4200 volts) to 2.5 cycles at 3728 kva. (5000 volts).

The arcing time may be even slower at lower voltage and current values, but these values illustrate the efficiency of my novel device.

In the foregoing I have described my invention solely in connection with illustrative embodiments thereof. Since many variations and modifica-

tions of my invention will now be obvious to those skilled in the art, I prefer to be bound not by the specific disclosures herein contained, but only by the appended claims.

5 I claim:

1. In a circuit breaker for protecting an electrical system, a first contact, a blow-out coil having one terminal connected to said first contact, a conductor having a U-shaped notch, an insulation block between said first contact and conductor for spacing said contact from said conductor, the second terminal of said coil being connected to said conductor, a movable contact for cooperating with said first contact, an arcing horn on said movable contact, the forward portion of said arcing horn extending into said U-shaped notch and spaced a predetermined distance from said conductor when said movable contact engages said first contact, said conductor being positioned above said first contact, a magnetic circuit energized by current flowing in said blow-out coil, said magnetic circuit including magnetic material extending from above said conductor downwardly toward said conductor so that on separation of the movable contact from said fixed contact in response to a fault current in said system being protected by said circuit breaker, the distance from said conductor to said arcing horn does not change substantially during the first movement of said movable contact and the arc formed between said fixed and movable contact is driven upwardly against said insulation block and to said conductor when said fixed and movable contact separation has reached a distance at which the impedance of the gap from said fixed contact to said conductor and from said conductor to the forward portion of said arc horn is less than the impedance from said fixed to said separated movable contact, the voltage drop across the gap from the fixed contact to said conductor produced by the arc thereacross appearing across said coil.

2. In a circuit breaker for protecting an electrical system, a first contact, a blow-out coil having one terminal connected to said first contact, a conductor having a U-shaped notch, an insulation block having slots at its open end, said block extending between said conductor and first contact for spacing said contact from said conductor, the second terminal of said coil being connected to said conductor, a movable contact for cooperating with said first contact, an arcing horn on said movable contact, the forward portion of said arcing horn extending into said U-shaped notch and spaced a predetermined distance from said conductor when said movable contact engages said first contact, said conductor being positioned above said first contact, a magnetic circuit energized by current flowing in said blow-out coil, said magnetic circuit including magnetic material extending from above said conductor downwardly toward said conductor so that on separation of the movable contact from said fixed contact in response to a fault current in said system being protected by said circuit breaker, the distance from said conductor to said arcing horn does not change substantially during the first movement of said movable contact and the arc formed between said fixed and movable contact is driven upwardly against said insulation block and to said conductor when said fixed and movable contact separation has reached a distance at which the impedance of the gap from said fixed contact to said conductor and from said conductor to the forward portion of said

arc horn is less than the impedance from said fixed to said separated movable contact, the voltage drop across the gap from the fixed contact to said conductor produced by the arc there-across appearing across said coil, said magnetic circuit including iron for said blow-out coil extending on both sides of the path of movement of said movable contact, substantially parallel thereto.
